WIRE STITCHING MACHINE

Robert Minkow, New York, N. Y.

Application December 11, 1942, Serial No. 468,712

6 Claims. (Cl. 1-2)

This invention relates to stapling machines.

An object of this invention is to provide an improved work support for a stapling machine so as to provide for the stapling of the work in the proper places.

This invention is designed especially as an attachment to a stapling machine employing a conventional stapling mechanism in which a wire brush is formed, the wire bristles being clamped between a pair of steel disks which are stapled together at circumferentially spaced points. This invention provides for holding the unstapled disks together and then supporting the disks so that they may be progressively rotated as the staples are driven therethrough.

This invention also provides for the support of the work in a manner whereby adjustment may be obtained to accommodate different sizes of disks.

This invention also provides for the latching of the rotary support, the latter being manually rotatable in only one direction.

This invention also provides for an attachment of this kind in which the support is both horizontally and vertically adjustable so as to provide the necessary adjustment range for different pieces of work.

To the foregoing objects and others which may hereinafter appear, the invention consists of the novel construction, combination and arrangement of parts as will be more specifically referred to and illustrated in the accompanying drawings, wherein are shown embodiments of the invention, but it is to be understood that changes, variations and modifications may be resorted to which fall within the scope of the invention as claimed.

In the drawings:

Figure 1 is a detail elevation, partly in vertical section, of an attachment for a stapling machine, constructed according to an embodiment of this invention;

Figure 2 is a sectional view taken on the line 2-2 of Figure 1;

Figure 3 is a sectional view taken substantially on the line 3-3 of Figure 2;

Figure 4 is a fragmentary sectional view taken on the line 4-4 of Figure 3;

Figure 5 is a sectional view taken on the line 5-5 of Figure 3;

Figure 6 is a sectional view taken on the line 6-6 of Figure 3;

Figure 7 is a sectional view taken on the line 7-7 of Figure 3;

Figure 8 is a sectional view taken on the line 8-8 of Figure 3.

Figure 9 is a fragmentary vertical sectional view similar to Figure 3, but on a larger scale;

Figure 10 is a fragmentary side elevation of the gage means at the rear of the machine.

Referring to the drawings the numeral 10 designates generally a stapling machine of conventional construction which includes a vertical column or standard 11 supporting a stapling structure 12 which opposes an anvil 13 positioned beneath the stapling mechanism 12.

The anvil 13 is supported from a bracket 14 which is carried by the column or standard 11.

15 The bracket 14 is provided at its inner end with a base 15 which engages a guide 16 carried by the forward side of the standard 10. The column 11 is formed with a pair of horizontally aligned guide passages 17 and 18 and the base 15 of the bracket 14 is provided with a boss 19 loosely engaging in the guide opening 17. A bracket holding bolt 20 engages through the two openings 17 and 18 and is threaded into the boss 19. Tightening of the bolt 20 will hold the bracket 14 in 25 vertically adjusted position with respect to the column or standard 11. The bracket 14 may be vertically adjusted along the column 11 by means of a threaded adjusting screw 21 which is threaded in an opening 22 formed in the lower 30 portion of the base 15. The adjusting screw 21 is formed with a knurled knob 23 adjacent the lower end thereof, and the adjusting screw 21 is formed with a reduced stud 24 which rotatably engages in a socket 25 carried by a forwardly projecting lug 26. The lug 26 is formed integral with or secured to the column 11 below the guide 16.

35 The anvil 13 is mounted in an opening 27 which is formed in the forward portion of the bracket 14 and the anvil 27 includes a reduced diameter stud 28 loosely engaging in a reduced opening 29 formed in the bracket 14. The upper side 30 of the bracket 14 constitutes the clinching table and the upper end of the anvil 13 is substantially flush with the upper side of the table 30.

40 In order to provide a means whereby the work which is being stapled may be rotatably supported with respect to the table 30 and the anvil 13, I have provided a vertically disposed shaft 31 which is rotatably mounted between a pair of bearing blocks 32 and 33. The bearing blocks 32 and 33 are disposed between a pair of forwardly projecting plates 34 and 35 and are secured therebetween by means of fastening members 36 and 50 37. The blocks 32 and 33 are aligned with respect

to each other by means of one or more dowel pins 38 which engage in sockets 39 formed in the confronting sides of the bearing blocks 32 and 33. The shaft 31 is hollow and is formed at its upper end with an annular flange 40 bearing against the upper ends of the blocks 32 and 33. The shaft 31 is formed with an enlarged lower portion 41 bearing against the lower end of the blocks 32 and 33 and a hand wheel 42 is secured, in any suitable manner, to the lower end of the shaft 31.

In the present instance the stapling machine is designed for stapling together a pair of disk-shaped plates 43 and 44 which engage on opposite sides of a plurality of radially arranged bristles 45. The bristles 45 are, in the present instance, formed of wire or steel and are firmly clamped between the two disks 43 and 44. The disks 43 and 44 are formed with aligned openings 46 and 47 respectively, and the disks are removably held on the upper end of the shaft 31 by means of a clamping structure. The clamping structure includes a lower plate 48 which rests on the upper side of the flange 40. The plate 48 is formed with a semi-cylindrical stud 49 which extends downwardly into the hollow shaft 31. The stud 49 is held against rotation with respect to the shaft 31 by means of a semi-circular plate 50 which is secured within the shaft 31 at the upper end thereof by means of a fastening member 51. The upper clamping plate 52 is adapted to engage against the upper side of the upper disk 43 and is formed with a stud 53 engaging through the openings 46 and 47. The stud 53 is also formed with a reduced threaded stud 54 which is threaded into the lower clamping plate 48.

In order to provide a means whereby the brush, which is formed by the bristles 45 clamped between the disks 43 and 44, may be rotated to provide for the circumferential position of the staples, I have provided a ratchet plate 55 which is secured to a plate 56 carried by the lower side of the wheel 42. The plate 56 is secured by fastening members 57 to the spokes of the handwheel 42 and the ratchet plate 55 is secured by fastening members 58 to the lower side of the plate 56. In the present instance, there are three annular series of ratchets 55, the purpose for which will be hereinafter described (see Figure 7).

The bearing block supporting plates 34 and 35 are adjustably mounted on the forward end of the bracket 14 by means of rearwardly projecting arms 59 and 60 which extend rearwardly from the plates 34 and 35 respectively. The arms 59 and 60 are formed with longitudinal keys 61 and 62 respectively, engaging in guideways 63 and 64 carried by the opposite sides of the bracket 14 below the table 30.

The arms 59 and 60 are formed with elongated slots or openings 65 and 66 respectively and a clamping bolt 67 engages through an opening 68 formed in the bracket 14 and loosely engages in the slots 65 and 66. A wing nut 69 is threaded onto the bolt 67 and preferably a flanged washer or bushing 70 is interposed between the nut 69 and the outer side of the arm 59.

The arms 59 and 60 are accurately adjusted lengthwise of the bracket 14 by means of a holding bolt 70. The bolt 70 engages loosely through an opening 71 formed in the arm 59 and the adjacent side of the bracket 14 is formed with a plurality of longitudinally spaced apart threaded sockets 72 within which the bolt 70 threadably

engages. The bolt 70 has a chain 73 secured thereto, the chain providing a means whereby the bolt 70 will not be lost when it is removed during the lengthwise adjustment of the arms 59 and 60. A pointer 74 which is secured by fastening means 75 to the arm 60, engages over the upper side of the table 30 rearwardly of the anvil 13, and is correlated with graduations 76 which are formed in the table 30.

The handwheel 42 is adapted to rotate in only one direction and is latched in its rotated position by means of a spring-pressed pawl 77 which is mounted in a sleeve 78. The sleeve 78 is formed with an L-shaped opening 79 in one side thereof, and a pin 80 carried by the pawl 77 loosely engages in the vertical portion of the L-shaped sleeve 79. The horizontal portion of the L-shaped slot 79 provides a means whereby the pawl 77 may be latched in a released position with respect to the ratchet 55. The sleeve 78 is formed with a reduced lower portion 81 engaging in an opening 82 formed in a horizontally disposed pawl supporting bar 83. The pawl 77 is provided with a reduced shank 84 slideable in the reduced sleeve 81, and a spring 85 constantly urges the pawl 77 to a latched position. Lock nuts 86 are threaded onto the lower end of the shank 84, and limit the upward movement of the pawl 77. The pawl supporting bar 83, at its rear end, is secured by means of a fastening member 87 to a boss 88, which is formed integral with the bracket 14. The intermediate portion of the bar 83 is supported from the bracket 14 by means of a pair of L-shaped supporting bars 89 which have their vertical sides 90 secured by a fastening member 91 to the bar 83.

The upper horizontal sides 92 of the supporting bars 89 are secured by fastening members 93 to a boss 94 formed integral with the bracket 14.

In the use and operation of this attachment the bracket 14 is vertically adjusted by means of the adjusting screw 21. The holding bolt 20 is initially loosened to permit vertical adjustment of the bracket 14 by rotation of the adjusting screw 21. The guide 16, at one side thereof, and the base 15, on the same vertical side, are provided with correlated gauge members 95 and 96 respectively which provide a means for accurately positioning the anvil 13 with respect to the stapling structure 12. The two disks 43 and 44 are clamped together with the wire bristles 45 engaging therebetween by threading the stud 54, carried by the upper clamping member 52, into the lower clamping member 48. The semi-circular stud 49 is then inserted in the hollow shaft 31, the semi-circular plate 50, which is fixed relative to the shaft 31, holding the clamping members 48 and 52 and the disks 43 and 44 against rotation with respect to the shaft 31.

As the staples are driven through the two disks 43 and 44 the operator of the mechanism is adapted to manually and progressively rotate the handwheel 42 which is turned in a clockwise direction for the distance of one notch in ratchet 55 for each staple.

In the present instance, the handwheel 42 is rotated in a clockwise direction, as viewed in Figures 1 and 2. By providing a plurality of concentrically arranged ratchet teeth on the plate 55 (see Figure 7), the pawl 77 will engage a correlated series of ratchet teeth when the work supporting structure, including the shaft 31 and the bearing blocks 32 and 33 are adjusted lengthwise of the bracket 14.

This device may be made as an attachment to

a conventional stapling machine, the standard of the machine being formed with the necessary guide means for the supporting bracket and the work rotating means hereinbefore described may be secured to the sides of the anvil supporting bracket.

This attachment will permit the rotation of the work at a point below the stapling head so that the operator will not be injured by rotating the work by contacting the hands directly with the work.

While this device has been designed particularly for use in assembling circular bristle brushes or circular wire brushes, it may also be used for stapling cloth buffering wheels, or other elements which are stapled together by means of a circular series of staples, regardless of the outer configuration of the article. In other words, it will be understood that the configuration of the article to be stapled is not a limiting factor in the use of this invention, and I do not wish to be limited to the particular uses herein set forth.

I claim:

1. In a wire stapling machine having a supporting standard, a stapling head and a staple clinching anvil, a bracket secured to said standard and formed with an anvil socket, a vertical shaft forwardly of said anvil, means rotatably mounting said shaft on said bracket, work clamping means removably engaging said shaft, and means for rotating said shaft.

2. In a wire stapling machine having a supporting standard, a stapling head and a staple clinching anvil, an anvil supporting bracket, a vertically disposed shaft forwardly of said anvil, horizontally adjustable means supporting said shaft forwardly of said anvil, work clamping means, correlated means carried by said clamping means and said shaft for holding said clamping means against rotation relative to said shaft, means for rotating said shaft, and ratchet means holding said rotating means against rotation in one direction.

3. In a wire stapling machine having a supporting standard, a stapling head and a staple clinching anvil, an anvil supporting bracket, a vertically disposed shaft forwardly of said anvil, horizontally adjustable means supporting said shaft forwardly of said anvil, work clamping means, correlated means carried by said clamping means and said shaft for holding said clamping

means against rotation relative to said shaft, a wheel fixed to said shaft, a ratchet fixed to said wheel, and a spring-pressed pawl carried by said bracket engaging said ratchet.

5. In a wire stapling machine having a supporting standard, a stapling head and a staple clinching anvil, an anvil supporting bracket, a vertically disposed shaft forwardly of said anvil, horizontally adjustable means supporting said shaft forwardly of said anvil, work clamping means, correlated means carried by said clamping means and said shaft for holding said clamping means against rotation relative to said shaft, a shaft operating wheel fixed to said shaft, an annular ratchet fixed to said wheel, a spring-pressed pawl engaging said ratchet, and a pawl supporting bar carried by said bracket.

10 5. In a wire stapling machine having a supporting standard, a stapling head and a staple clinching anvil, an anvil supporting bracket, a vertical hollow shaft forwardly of said anvil, a pair of bearing blocks for said shaft, a pair of bearing supporting plates, rearwardly extending supporting means carried by said plates and engaging on opposite sides of said bracket, means 20 adjustably securing said arms lengthwise of said bracket, work clamping means seating on the upper end of said shaft, correlated means carried by said clamping means and said shaft holding said clamping means against rotation relative to said shaft, and means for rotating said shaft.

15 6. In a wire stapling machine having a supporting standard, a stapling head and a staple clinching anvil, an anvil supporting bracket, a vertical hollow shaft forwardly of said anvil, a pair of bearing blocks for said shaft, a pair of bearing supporting plates, rearwardly extending supporting means carried by said plates and engaging on opposite sides of said bracket, means 30 adjustably securing said arms lengthwise of said bracket, work clamping means seating on the upper end of said shaft, correlated means carried by said clamping means and said shaft holding said clamping means against rotation relative to said shaft, said correlated means including a depending stud carried by said clamping means, means carried by said shaft holding said stud against rotation relative to said shaft, and means 35 for rotating said shaft.

40 50 ROBERT MINKOW.
